(57) CLAIM

The ornamental design for a label, as shown and described.

DESCRIPTION

FIG. 1 is a front plan view of a first embodiment of a label; and,

FIG. 2 is a front plan view of a second embodiment of a label. The broken line showing of environmental structure in the figures is for illustrative purposes only and forms no part of the claimed design.

1 Claim, 2 Drawing Sheets

FIG. 1

FIG. 2
